US0D1044976S

(12) **United States Design Patent** (10) **Patent No.:** **US D1,044,976 S**
(45) **Date of Patent:** **** Oct. 1, 2024**

(54) **WATER DUMBBELL**

(71) **Applicant:** **Shenzhen Dreamstone International Co., Ltd**, Guangdong (CN)

(72) **Inventor:** **Yingzi Li**, Guangdong (CN)

(**) **Term:** **15 Years**

(21) **Appl. No.:** **29/931,648**

(22) **Filed:** **Mar. 7, 2024**

(30) **Foreign Application Priority Data**

Jan. 17, 2024 (CN) 202430031967.0

(51) **LOC (14) Cl.** **21-02**

(52) **U.S. Cl.**

USPC **D21/681**; D9/531

(57) **CLAIM**

The ornamental design for a water dumbbell, as shown and described.

DESCRIPTION

FIG. 1 is a perspective view of the water dumbbell showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

(Continued)

The broken lines in the figures illustrate portions that form no part of the claimed design.

1 Claim, 7 Drawing Sheets
